SWITCHING AND STARTER APPARATUS OF ELECTRIC MOTORS

Filed Aug. 28, 1926.

FIG.1.

FIG.2.

FIG.3.

Patented June 14, 1927.

UNITED STATES PATENT OFFICE.

HELIER OSWALD BREE, OF AUCKLAND, NEW ZEALAND.

SWITCHING AND STARTER APPARATUS OF ELECTRIC MOTORS.

Application filed August 28, 1926, Serial No. 132,226, and in New Zealand July 31, 1926.

This invention relates to the switching and starter apparatus for electric motors and has been devised to eliminate the danger and damage to apparatus and machinery by the 5 possibility of putting into operative position the main switch when the starter itself is already in the "on" or in any intermediate position.

When the main switch is put "in" and the 10 starter is inadvertently not in the normal "off" position there is a resultant heavy rush of current to the switch, starter, wiring of the motor, and other adjacent parts and there is a grave possibility of such rush causing 15 fusing of the parts or burning out of the armature and in some instances even injury to the person putting in the switch. The possibility of this error happening is by no means slight and is especially likely when 20 the starter must be returned to the "off" position manually.

The invention which may be adapted to the main switch controller and starter of any usual type of electric motor is so devised that the main switch is prevented from 25 being put into operative position when the power supply is off and/or when starter is at any other than the correct "off" position.

The idea underlying this invention which 30 may be adapted to any usual type of main switch and starter apparatus for electric motors is to provide means whereby the above disadvantages and dangers are eliminated and to provide means whereby the main 35 switch remains locked in an inoperative position while either the main power supply is cut off from any cause and/or while the starter is not in its "off" position. By this invention the operator can at once tell by 40 the impossibility of throwing into operative position the main switch that either or both of the above contingencies have occurred.

The invention consists in these salient features and in the further features and arrangements and combinations of parts hereinafter described, and more particularly 45 pointed out in the claims.

Referring to the accompanying drawings which illustrate one constructional embodiment incorporating the principle underlying 50 the invention, Figure 1 is a sectional end view of a common main switch with the safety means in position, Figure 2 is a perspective view of a common form of starter 55 with the safety means in position, and Fig-

ure 3 is a view partially in perspective showing the working parts in position and the wiring arrangement.

Referring now to the drawings a common type of main switch 1 is illustrated having 60 four contacts 2, 3, 4, and 5 and a leader 6 with two U contact plates 7 and 8, a handle 9 swivelled on pin 10 to the lever 6 being provided. The plates 7 and 8 engage in the pairs of contacts 2, 3, and 4, 5 respectively 65 in the usual way. The said switch 1 is provided with a lug 11 on its cover 12 to which is pivotally mounted a movable catch lever 13 carrying an armature 14, on its outer face, and a stop piece 15 at its inner upper end 70 and a projection or flange 16 at its inner lower end having an inclined outer face 17. Means such as a spring 18 or the like attached to said lever 13 and to cover 12 tend 75 to draw the latter towards said cover. A 75 projection 19 with an inclined upper face 20 is provided on lever 6. Also attached to said cover 12 is an electric magnet 21 so arranged and disposed as to be in close proximity to said armature 14 which it attracts 80 when energized. The handle 9 of the switch 1 is provided with contact make and break means such as a push button 22 normally kept from making contact with its contact piece 24 in said handle by means such as a 85 spring 23.

Referring now to the starter portion of the apparatus a common type of starter 25 has an insulated contact box 28 fitted on its outer face said box 28 being provided with 90 a spring contact 29 and also a plunger contact 30 with a knob 31 projecting therefrom a spring 32 or the like means pressing between the latter and the box 28 tending to 95 keep the contacts 29 and 30 apart.

The starter lever 27 has a quadrant or the like 26 which is so disposed in relation to said knob 31 as to bear against it when the starter is in the "off" position and thus 100 against the action of the spring 32 keep the contacts 29 and 30 together. The main supply power wires 33 and 34 pass to the contacts 2 and 4 respectively and wires 24 and 26 pass from the terminals 3 and 5 to the starter 25 and from thence to the motor 45. A wire 37 passes from the terminal 2 to the contact piece 24 while a wire 38 passes from the push button 22 to one end 39 of the winding of the electromagnet 21. A wire 40 passes from the other end 41 of said electro-

magnet 21 winding to the spring contact 29 while a further wire 42 passes from the plunger contact 30 to the terminal 4.

Assuming for the moment that power is "on" in the main wires 33 and 34 and the main switch 1 and the starter 25 to be both in the "off" position as shown in Figures 1 and 2 the spring 18 naturally draws the lever 13 so that its projection 16 is over the projection 19 of the switch lever 6 thereby making it impossible for the switch 1 to be put "on" by moving the handle 9 in the direction of the arrow shown in Figure 1. To start the apparatus it being assumed that both the power is "on" and the starter is in the "off" position the push button 22 is pressed downwardly thereby energizing the electromagnet 21 which attracts the armature 14 thus drawing the ends 16 of the lever 13 out of juxtaposition with the projection 19 of said lever 6 thus enabling the switch 1 to be pushed in the direction shown by the arrow in Figure 1 into the "on" position.

It will be obvious that the energizing of said electromagnet 21 is caused by the push button 22 making contact with the contact piece 24 current thereby passing from wire 37 to wire 38 and from thence to the electromagnet 21 end 39. Current also passes from wire 32 through plunger to spring contact 29 these two always touching each other when the starter 25 is in the "off" position, the current then passing from the contact 29 to the electromagnet 21 and 41 by way of wire 40 completes the electrocircuit and energizing said magnet 21. The main switch 1 being "on" the handle 9 is released and the spring 23 forces the push button 22 away from the contact 24 and the circuit to the electromagnet 21 is thus broken.

It will be noticed that when the starter handle 27 is moved on the quadrant 26 passes clear of the knob 31 and the spring 32 forces plunger contact 30 away from the spring contact 29 and when the main switch 1 is on the lever 13 is drawn by a spring 18 until stop 15 is against the cover 12.

On the main switch 1 being switched off the inclined piece 20 of the lever 6 and the inclined piece 17 of the catch lever 13 come together and the latter is forced outwardly against the tension of its spring 18 until the projection 16 slides over the projection 19 thereby locking the main switch until the

electromagnet 21 is again energized. It will be noted that at all times unless the quadrant 26 of starter 27 is pressing knob 31 so that contacts 29 and 30 are touching the main switch 1 cannot be moved "on" even though push button 22 is pressed as the latter only closes part of the circuit and the operator of the switch on it being still locked will at once know that as he is unable to put on the main switch 1 either because the starter is not in its normal "off" position or because the current is not flowing through the main wires.

Claims:

1. In combination with a circuit breaker 70 for opening and closing an electric circuit, a handle for said circuit breaker, a starting resistance, a controller arm for varying said resistance, a latch for holding said circuit breaker in open position, an electromagnet 75 adapted when energized to release said latch, a pair of circuit closing switches in series with said electromagnet and normally open when said resistance is cut out, means on said handle for closing one of said switches, 80 and means on said controller arm for closing the other of said switches when the resistance is in series with the circuit.

2. In combination with a circuit breaker for opening and closing an electric circuit, a handle for said circuit breaker, a starting resistance, a latch for holding said circuit breaker in open position, an electromagnet adapted when energized to release said latch and a pair of circuit closing switches in series with said electromagnet, one of said switches being disposed within said handle, the other of said switches being open when a portion of said resistance is cut out.

3. In combination with a circuit breaker 95 for opening and closing an electric circuit, a handle for said circuit breaker, a starting resistance, a latch for holding said circuit breaker in open position, an electromagnet adapted when energized to release said latch, 100 a pair of circuit closing switches in series with said electromagnet, one of said switches being disposed within said handle and being normally open, means on said handle for closing the switch in the handle, and means for holding open the other of said switches when a substantial portion of said resistance is cut out.

In testimony whereof I affix my signature.
